C. Francis Jenkins

UNITED STATES PATENT OFFICE.

CHARLES FRANCIS JENKINS, OF WASHINGTON, DISTRICT OF COLUMBIA.

GRID COUPLED CELL CIRCUIT.

Application filed October 22, 1924. Serial No. 745,209.

This invention relates to radio circuits in which a light-sensitive cell is employed to modulate the circuit, and its principal object is to so control the circuit as to interrupt a continuous wave as though it were "key modulated".

With this, and other objects in view, the arrangement of the elements of the circuit is described herein, illustrated in the drawing, and particularly pointed out in the claims.

The whole is a system for controlling an oscillator of radio frequency by the action of light on a light-sensitive cell. It employs an oscillator circuit and a cell circuit, the two coupled through a variable (grid leak) resistance. In the drawing A is a light-sensitive cell; B a battery in the cell circuit; C a variable resistance, through which the cell circuit is coupled to the grid circuit of the tube D.

With the cell A in the dark, the coupling resistance is adjusted until the tube circuit is oscillating. When the light falls on the cell 25 the balance of circuit A, B, C is upset (because the resistance of the cell falls when light falls thereon) and the oscillation of the tube circuit ceases.

No means is shown for cutting the light off the cell (one's hand would answer), as this is no part of the invention, or required for an understanding of its operation.

What I claim, is—

1. The method of signalling by means of a high frequency oscillation generator controlled by a light sensitive cell, including the step of setting up oscillations under dark conditions of the cell and suppressing oscillations by projecting light upon said cell.

2. In the method of transmitting signals or the like involving the use of radio frequency oscillations, the step which includes interrupting the oscillations in accordance with light transmission from a given source. 45

3. In the method of transmitting signals or the like including the use of a thermionic oscillation generator having a light influenced balanced current path normally operative in the absence of light to permit oscillations, the step which includes interrupting oscillations by energizing one of the current paths by a light responsive current generator. 50

4. The combination, in an oscillation generator, including coupled input and output circuits, of an auxiliary circuit containing a light sensitive cell conductively coupled thereby to the input circuit, a source of potential in the auxiliary circuit, and a resistance bridged across the input and auxiliary circuit, said resistance being adjusted to a value to permit the generator to oscillate when the cell is dark and to arrest oscillations when the cell is influenced by light. 55

5. The combination with an electron valve, of an oscillation circuit including the grid and filament electrodes of said valve, a cell circuit, a light sensitive cell in said cell circuit, a battery in said circuit, and a resistance bridged across said circuits and normally adjusted to a value to permit the oscillation circuit to oscillate when the resistance of the cell is at maximum. 65

In testimony whereof I have affixed my 75 signature.

CHARLES FRANCIS JENKINS.
